UNITED STATES PATENT OFFICE.

SAMUEL H. HAMER, OF BELLINGHAM, WASHINGTON, ASSIGNOR OF ONE-HALF TO
GEORGE SIDNEY STARK, OF BELLINGHAM, WASHINGTON.

RECEIVER ATTACHMENT FOR TELEPHONES.

1,333,805.

Specification of Letters Patent. Patented Mar. 16, 1920.

Application filed November 5, 1918. Serial No. 261,229.

To all whom it may concern:

Be it known that I, SAMUEL H. HAMER, a citizen of the United States, and a resident of Bellingham, in the county of Whatcom and State of Washington, have invented 5 certain new and useful Improvements in Receiver Attachments for Telephones, of which the following is a specification.

The present invention relates to 10 telephony, and has particular reference to an attachment for telephone stands for supporting the receiver in proper position from the stand.

An object of the present invention is to 15 provide an attachment of this character which, when used, admits of the free use of both hands for writing and other purposes, while carrying on a conversation on the telephone.

20 Another object of the present invention is to provide a relatively simply constructed attachment comprising but few parts, and which may be readily applied to telephone stands of ordinary construction, without 25 alteration or change in the construction of the stand.

The above, and various other objects and 30 advantages of this invention will be in part described, and in part understood, from the following detailed description of the present preferred embodiment, the same being illustrated in the accompanying drawings, wherein:

Figure 1 is a side elevation of an ordinary telephone stand, having the attachment 35 of this invention applied thereto, the dotted lines disclosing the attachment in raised operative position.

Fig. 2 is a rear elevation of the stand, 40 showing the attachment in normal position and in engagement with the receiver hook for holding the same in depressed position.

Fig. 3 is a fragmentary sectional view 45 through the upper end of the telephone stand and the attachment as applied thereto.

Fig. 4 is a transverse section taken substantially on the line 4—4 of Fig. 3.

Fig. 5 is a transverse section taken on the line 5—5 of Fig. 3.

50 Fig. 6 is a rear elevation of a telephone stand having a slightly modified form of the attachment applied thereto.

Fig. 7 is a transverse section through 55 the modified form of the attachment, taken on the line 7—7 of Fig. 6.

Referring to these drawings, wherein like parts are designated by similar characters of reference throughout the several views, A designates a telephone stand of the usual type, provided with a receiver hook or 60 telephone circuit making and breaking lever B projecting from one side thereof, and having a transmitter C mounted upon the upper end thereof.

The upper end of the standard A is provided with a pair of forked arms 10 and 11 having transversely registering openings of like size therethrough, the opening in the fork arm 11 being provided at one side with a keyway, as shown in Fig. 3. The shank 70 D of the transmitter C is fitted in the usual manner between the fork arms 10 and 11, and is suitably apertured for the reception of a pivot pin 12. The pivot pin 12 extends through the fork arm 11, the shank 75 D, and into the opening in the fork arm 10, but is relatively short and does not extend entirely through the latter. A relatively small screw 12^a extends through the fork arm 10 and into the inner threaded 80 end of the pivot pin 12. The pivot pin 12 is held from turning in the fork arm 11 by the provision of a laterally extending feather or key 13 engaging in the keyway 85 in the fork arm 11, and a locking washer 14 is fitted over the pin 12, against the outer side of the fork arm 11. As shown to advantage in Figs. 3 and 4, the locking washer 14 is provided with an outer serrated or toothed surface, and has a keyway 90 communicating with one side of the central opening therethrough for the reception of a feather or key 15 projecting from the pin 12 for holding the washer 14 from turning upon the pin. The key 15 is preferably arranged at an angle from the key 13, and is adapted to abut against the outer face of the fork arm 11 to hold the pin 12 in place.

A supporting arm 16 is provided with a 100 rounded flat head 17 upon its inner end which is apertured, and which is adapted for engagement over the pin 12. The head 17 has an inner serrated or toothed surface adapted to mesh with the serrations or 105 teeth of the locking washer 14, for holding the arm 16 in adjusted position when swung about the pin 12.

A spring washer 18 is fitted over the pin 12 against the outer side of the head 17, 110

and is held under tension thereagainst by a binding nut 19. The binding nut 19 is provided with a peripheral milled or serrated surface adapted to receive the fingers 5 thereagainst for turning the nut 19 to tension the spring 18.

The inner end of the arm 16, which emerges from the head 17, is arcuate in form to provide a cam surface 20 for sliding 10 engagement over the upper edge of the receiver hook B for the purpose of depressing the latter when the arm 16 is swung down as shown in Fig. 1. The free end of the arm 16 is offset outwardly from the base 15 portion of the stand A, and is provided with a longitudinal slot 21 adapted to receive therethrough a threaded stem 22 projecting from the rear side of a relatively flat receiver E, a binding nut 23 being placed 20 upon the stem 22 and engaging against the outer side of the arm 16, to secure the receiver E in longitudinally adjusted position upon the arm. The arm 16 is provided at suitably spaced-apart points with apertured lugs or loops 24 adapted to receive therethrough the cord or cable F of the telephone for carrying the same to the receiver E.

In Figs. 6 and 7, a slightly modified form 30 of the attachment is shown, and which is in the form of an attachment to be applied to the arm 16. The same comprises a bracket 25. The bracket 25 may be in the form of a sheet metal blank comprising an elongated body bar having laterally extending straps 26 and 27 upon the opposite ends thereof adapted for engagement about the opposite ends of a relatively long receiver, such as is now commonly employed. The ends of the straps 35 26 and 27 are turned outwardly to form ears 28, as shown in Fig. 7, and through which pass clamping bolts 29 for binding the straps 26 and 27 upon the receiver to support the same. One end of the bracket 40 25, preferably the end with the larger loop 26, has an outturned attaching lug 30 adapted for engagement against the side of the arm 16, and through which may be passed a clamping bolt 31. When this modified form of attachment is employed, the loop 45 26 is preferably made of sufficient size to engage against the outer end of the receiver G and the loop 27 is relatively small to engage about the inner portion thereof.

50 The operation of the device is apparent, for when the telephone is to be used, the arm 16 may be swung into the dotted-line position shown in Fig. 1, and the nut 19 is tensioned against the spring 18 sufficiently 55 to bind the arm 16 in raised position for supporting the receiver. As the free end of the arm 16 is offset outwardly from the standard A, the receiver E, or G, is supported in proper position against the ear 60 while the mouth is directly opposite the

transmitter C. When the telephone stand A is placed upon a desk, table, or the like, both hands of the person using the telephone, are free to take notes or to perform other such functions. When it is necessary 70 to support the telephone in the hand, but one hand is necessary to hold the standard A.

When the arm 16 is swung down into an out of the way position, the cam surface 20 75 thereof engages the receiver hook B, and depresses the same for cutting out the telephone. As soon as the arm 16 is raised, however, the receiver hook B is free to rise in the usual manner.

80 It is of course understood that various changes and modifications may be made in the details of construction of the above specifically described attachment, without departing from the spirit of this invention, 85 and being restricted only by the scope of the following claims.

I claim:

1. The combination with a telephone stand, transmitter and receiver, of a pin pivotally supporting said transmitter on said stand, and an arm pivotally mounted upon said pivot pin and supporting the receiver, said arm mounted to swing independently 90 of the transmitter.

95 2. The combination with a telephone stand, transmitter and receiver, of a pin pivotally supporting said transmitter on said stand, an arm pivotally mounted upon the pivot pin of said transmitter, means for connecting said receiver to said arm to permit adjustment of the receiver longitudinally on the arm, said arm mounted to swing independently of the transmitter.

100 3. The combination with a telephone stand having an apertured portion at its upper end, a pin fitting in the apertured portion, means for holding the pin from turning, a locking washer keyed upon the pin and having an outer serrated surface, a 110 supporting arm pivotally mounted on the pin and having a serrated surface adapted to engage the serrated surface of the washer, a spring washer mounted upon said pin, a binding nut mounted upon the outer end of the pin and adapted for engagement against the spring washer to tension the same, and means on the outer end of the arm for engaging a telephone receiver.

115 4. In an attachment as specified, the combination with a telephone stand having a transmitter on the upper end thereof and a receiver, of a pin projecting from the upper end of the stand, an arm hingedly mounted on the pin, a spring washer mounted upon said pin, means for tensioning said spring washer for retaining the arm in various adjusted positions upon the pin, and means for adjustably holding a receiver upon the outer end of the arm.

5. In a telephone attachment, the combination of a telephone stand having a transmitter on its upper end, and a hook projecting from the side of the stand, and a receiver, of an arm pivotally mounted upon the upper end of the telephone stand and adapted to support the receiver, said arm shaped to form a cam portion thereon for engaging said receiver hook for retaining 10 the same in depressed position when the arm is swung down.

6. The combination with a telephone stand, transmitter, receiver, and telephone

circuit making and breaking lever extending exteriorly of said stand, of a receiver supporting arm pivotally carried by said stand, at its upper end portion, the inner ends of said arm where it emerges from said stand being arcuate in form to provide a cam surface for sliding engagement over the upper 15 edge of said circuit making and breaking lever, to depress said lever when the arm is down and permit said lever to rise when the arm is swung upwardly.

SAMUEL H. HAMER.
